UNITED STATES PATENT OFFICE.

WILLIAM PARKIN, OF TAUNTON, MASSACHUSETTS, ASSIGNOR TO REED & BARTON, OF SAME PLACE.

DESIGN FOR COFFIN-PLATES.

Specification forming part of Design No. 7,397, dated April 28, 1874; application filed March 31, 1874.

[Term of Patent 7 years.]

CASE A.

To all whom it may concern:

Be it known that I, WILLIAM PARKIN, of Taunton, in the county of Bristol and State of Massachusetts, have invented a Design for Coffin-Plates, of which the following is a specification:

The invention relates to the plates which are usually appended to and fastened upon the covers of coffins for the purpose of receiving the superscription.

The invention will first be fully described, and then pointed out in the claims.

The figure represents a plan view of my invention.

D represents a smooth face, on which is engraved the inscription, made of an irregular oblong form, but with curved outlines, and pointed (though not sharply pointed) ends *a a*. At each end is a flat frosted or otherwise ornamented surface, B, bounded by a series of

successively enlarging ribs, b, conjoined at each side to a pointed leaf, C. At the top and bottom is located a rounded and plain face, D. The ribs *b* are located at top and bottom.

What I claim as my invention is—

1. As a new design in coffin-plates, the smooth face D, frosted surface B, and ribs *b*, arranged as shown and described.
2. The top and bottom leaves C C, arranged on an oblong coffin-plate, as shown and described, to form a new design.
3. A border consisting of ribs *b* at top and bottom, with intermediate pillars E E, arranged on the sides of an oblong coffin-plate, as shown and described, to form a new design.

WILLIAM PARKIN.
